[57] CLAIM

The ornamental design for a combined digital audio disc player, radio tuner and tape recorder, as shown and described.

DESCRIPTION

FIG. 1 is a top, front and right side perspective view of a combined digital audio disc player, radio tuner and tape recorder according to the present invention;
FIG. 2 is a front elevational view thereof;
FIG. 3 is a top plan view thereof;
FIG. 4 is a rear elevational view thereof;
FIG. 5 is a bottom plan view thereof;
FIGS. 6 and 7 are left and right side elevational views thereof, respectively;
FIG. 8 is a top, front and right side perspective view of the combined digital audio disc player, radio tuner and tape recorder hereof, illustrating the speakers separated from the central control section;
FIG. 9 is a right side elevational view of the central control section, with the left side being the mirror-image thereof; and,
FIG. 10 is a left side elevational view of the righthand speaker illustrated in FIG. 8, with the right side of the lefthand speaker being the mirror-image thereof.
